UNITED STATES PATENT OFFICE.

GUSTAV SACHSENRODER, OF BARMEN-UNTERBARMEN, GERMANY.

PARCHMENT BUTTON.

1,079,365.

Specification of Letters Patent.

Patented Nov. 25, 1913.

Application filed January 4, 1912. Serial No. 669,445.

To all whom it may concern:

Be it known that I, GUSTAV SACHSENRODER, a subject of the German Emperor, and residing at Barmen-Unterbarmen, Germany, have invented certain new and useful Improvements in Parchment Buttons, of which the following is a specification.

The subject-matter of my invention is an improved clothes-button or linen-button. 10 The novel feature of the invention consists in the button being formed of vegetable parchment, which is organically or structurally united during its manufacture on one or both sides with linen or a like fabric. To effect such union I preferably parchmentize the parchment and textile fabric together.

In the drawing, Figure 1 is a plan view and Fig. 2 is a diametral section through the 20 improved button.

a designates the parchment, *b* the textile covering and *c, c* the sewing holes.

The button is manufactured by its being stamped out, and pressed from a sheet of 25 vegetable parchment which has been organically or structurally united, or parchmentized, during its manufacture with the textile material, the outer edge of the button being simultaneously rounded off and the 30 button impressed if desired. During the same operation the sewing holes *c, c* are punched.

The button, which may be manufactured in any color, is fully capable of resisting the effects of the washing water, is exceedingly durable both when in use, and when the article of clothing to which it is attached is mangled, and is exceedingly cheap to manufacture. It has, moreover, the advantage that the textile material which has 35 been organically united to the vegetable parchment does not become worn off nor worn through. When covered on both sides, the button has the advantage that it presents on both sides the same appearance. 40

I claim:—

1. A button consisting of a piece of vegetable parchment, and a covering of textile fabric structurally united thereto during 50 the manufacture of said parchment.

2. A button consisting of a piece of vegetable parchment, and a covering of textile fabric parchmentized thereto during the manufacture of said parchment. 55

In testimony whereof, I affix my signature in the presence of two witnesses.

GUSTAV SACHSENRODER. [L. S.]
